UNITED STATES PATENT OFFICE.

JOHN J. PERRY, OF BOSWORTH, MISSOURI.

SAND-EXCLUDER.

1,379,477.

Specification of Letters Patent. Patented May 24, 1921.

Application filed January 11, 1919. Serial No. 270,653.

To all whom it may concern:

Be it known that I, JOHN J. PERRY, a citizen of the United States, residing at Bosworth, in the county of Carroll and State 5 of Missouri, have invented certain new and useful Improvements in Sand-Excluders; and I do hereby declare the following to be a full, clear, and exact description of the invention, such as will enable others skilled 10 in the art to which it appertains to make and use the same.

My invention relates to a well pump attachment having means for effectively preventing the sucking of sand by a well pump.

15 An important object of this invention is to provide an attachment for well pumps adapted to exclude all sand and so forth from the pump pipe thereby preventing the same from being pumped up with the water.

20 A further object of this invention is to provide means of the character described which are easy to attach to a well pump pipe, durable in use, and of highly simplified construction.

25 Other objects and advantages of the invention will be apparent during the course of the following description.

In the accompanying drawings forming a part of this specification and in which like 30 numerals are employed to designate like parts throughout the same,

Figure 1 is a side elevation of a well pump pipe attachment embodied in my invention, and

35 Fig. 2 is a central vertical longitudinal section through the same.

In the drawings wherein for the purpose of illustration is shown the preferred embodiment of my invention, the numeral 5 40 generically designates my improved well pump pipe attachment, which in manufacture may be of any desired material and of any suitable size. The attachment comprises a cylindrical casing 6 having an imperforate 45 bottom 7. The upper portion of the casing 6 is provided with external screw threads 8 engaging interiorly disposed screw threads 9 carried by the lower portion of a coupling member 10. The coupling member 10 is 50 adapted for attachment to a well pipe through the medium of the interiorly screw-threaded nut 11 formed integral with the reduced end portion 12 of the same. Circular 55 openings 13 are disposed about the cylind-

rical casing 6 at a point spaced upwardly 55 from its bottom. A non-rusting wire mesh 14 is arranged over the openings 13 and is adapted to exclude particles of sand and the like from the interior of the casing. A pipe 15 is disposed with the cylindrical casing 6 60 and is of a considerably less diameter than the same. As shown in Fig. 2, the lower end of the pipe 15 is open and is spaced upwardly from the imperforate bottom 7 of the casing 6. The pipe 15 has threaded 65 engagement at its upper end portion thereof with a suitable pipe supporting circular plate 16. The pipe supporting plate 16 is provided with an annular flange 17 resting upon the upper end of the casing 6. An in- 70 teriorly disposed annular shoulder 18 carried by the coupling member 10 is adapted for contact with the annular flange 17 carried by the pipe supporting plate 16. The upper surface of the member 16 is provided 75 with a valve seat 19 receiving a leather valve 20 of the check valve type.

In the use of my improved well pump attachment it will be apparent that the same is attached to the well pipe and arranged in 80 the bottom of the well. Only that water above level of the openings 13 will be permitted to enter the interior of the cylindri- 85 cal casing 6.

Upon the creation of a suction, the water 85 passes upwardly through the pipe 15 as indicated by the arrows and subsequently through the coupling 10 of the well pump.

While I have shown and described the preferred embodiment of my invention, it 90 is understood that I may make such minor changes in arrangement and construction of parts, as will remain within the spirit of the invention and scope of the appended claim.

Having thus described my invention, what I claim is:—

A sand excluder comprising a cylinder having its lower end closed and its upper end open and externally screw threaded, means 100 for admitting fluid to the interior of the cylinder adjacent its upper end, a coupling cap threaded to the upper end of the cylinder, an internal shoulder formed in said cap and spaced from the upper end of said cylinder, a valve seat secured between said shoulder and the upper end of the cylinder 105 by the attaching of the cap to the latter,

said seat having a centrally arranged screw threaded bore, a check valve for said seat, and a tube threaded in said bore and extending downwardly in the cylinder to a point adjacent the closed end thereof and of a diameter considerably less than the diameter of the cylinder.

In testimony whereof I affix my signature in presence of two witnesses.

JOHN J. PERRY.
